PAPER CLIP

Henry G. Lankenau, Verona, N. J., assignor to
Noesting Pin Ticker Co. Inc., Mount Vernon,
N. Y., a corporation of New York

Application November 23, 1933, Serial No. 699,333

1 Claim. (Cl. 24—261)

This invention relates to improvements in paper clips and particularly to clips formed by bending a length of spring wire into a plurality of loops, two of the loops being spaced a comparatively short distance apart and lying in nested relation in the same plane, the said loops being adapted to be spread apart laterally of the clip, thereby to receive and grip two or more sheets of paper therebetween. This application is a continuation in part of my application Serial No. 663,141, filed March 28, 1933.

An object of this invention is to provide a paper clip made of a length of spring wire bent to form elongated outer and inner oblong members arranged in nested and operative relation with respect to each other, one end portion of the clip consisting of a single loop of rectangular form and the opposite end portion consisting of a double loop and being V-shaped in lengthwise direction.

Another object of this invention is to provide a spring wire clip having two spaced V-shaped loops at one end, the said end providing a wedge action and being adapted to be more easily applied to two or more papers than the type of clip generally known in the art as "Gem" clips and having U-shaped loops.

Another object of this invention is to provide a spring wire clip having a rectangular end portion, the two ends of the wire terminating in a plane lying substantially in abutment with the said rectangular end so as to provide maximum gripping surface and prevent the ends of the spring wire from digging into the papers to which the clip is attached.

With the above and other objects in view, the invention will be hereinafter more particularly described and the formation and arrangement of the V-shaped loops will be shown in the accompanying drawing and pointed out in the claim which forms part of this specification.

Reference will now be had to the drawing, wherein like numerals of reference designate corresponding parts throughout the several views, in which:

Figure 1 is a plan view of a paper clip.

Figure 2 is a side view of the clip shown in Figure 1.

Figure 3 is a plan view of a portion of two or more sheets of paper having the clip shown in Figure 1 applied thereto.

Figures 4, 5, 6 and 7 are plan views of modified clips.

Figure 8 is a perspective view of a modification of the clip shown in Figure 4.

Figure 9 is a perspective view of a modification of the clip shown in Figure 5.

In the illustrated embodiment of the invention, Figures 1 to 3, inclusive, show a spring wire clip 1, which is bent from a single piece of wire of suitable diameter and stiffness. The clip consists of an outer clamping member 2, and an inner clamping member 3, lying within the outer member in such a manner that the wires touch. The outer and inner members are united by a straight cross-bar 4, adapted to straddle the edge of a number of papers to which the clip may be applied. The outer clamping member 2 consists of two spaced parallel legs 5 and 6, united by a V-shaped loop 7, the leg 5 being a connection between the cross-bar 4 and loop 7. The inner clamping member 3 consists of two spaced parallel legs 8 and 9, united by a V-shaped loop 10. The free end 11 of the outer clamping member 2, and the free end 12 of the inner clamping member 3 terminate in a plane lying substantially in abutment with the straight cross-bar or end 4. As shown in Figures 1 and 2, the cross-bar 4 and the loops 7 and 10, and the four legs 5, 6, 8 and 9 of the clip 1, lie in a common plane when not in use. As shown in Figure 3, the clip 1 is applied to two or more sheets of paper 13 by springing the inner member 3 away from the outer member 2 laterally of the clip, so that the V-shaped loop 7 will engage the top of the uppermost sheet while the V-shaped loop 10 will engage the underside of the bottom sheet, thus clamping the sheets 13 between the loops 7 and 10. The cross-bar 4 lies closely against and straddles the edge 14 of the papers 13 to which the clip is applied and there is no chance for accidental displacement of the clip.

As shown in Figure 4, there has been provided a modified paper clip 15 similar to the clip 1, but having an outer loop bent inwardly at 16 in a lengthwise direction and forming two prongs or fingers 17, 18, extending longitudinally outwardly from the outer clamping member 19. The inner clamping member 20 has a V-shaped loop 21 similar to the loop 10 in the clip 1. It will be noted that the two prongs or fingers 17, 18, serve as guides for the V-shaped end 21 and cause the clip 15 to move in a straight line as directed by the force exerted by the user against the rectangular end or handle 22.

As shown in Figure 5, there has been provided a modified clip 23 similar to the clips 1 and 15, but having a straight cross-bar 24 on the outer clamping member 25. The inner clamping member 26 has a V-shaped loop 27 similar to the loop

21 on the clip 15. It will be noted that the straight cross-bar 24 has a straight end wall facing outwardly and is also adapted to exert a steadyng effect on the motion of the V-shaped 5 end 27 so as to cause the clip 23 to move in a straight line as directed by the force exerted by the user against the rectangular end or handle 28.

It is to be noted that better results may be obtained in guiding the clips 15 and 23 in a straight line by slightly bending the prongs or fingers 17 and 18 of the clip 15 or the end 24 of the clip 23 in a direction laterally of said clips as shown in Figures 8 and 9. It is also to be noted that the free ends 11¹, 12¹, of the clip 15 terminate in a plane lying in abutment with the rectangular end 22, and that the free ends 11², 12², of the clip 23 terminate in a plane lying in abutment with the straight end 28. It is also to be noted that the side elevations of the clips 15 and 20 23 lie respectively in a single plane as shown in Figure 2.

As shown in Figure 6, there has been provided a modified paper clip 29 similar to the clip 15 shown in Figure 4, but having an outer loop 30 bent into V-shape and lying inwardly in lengthwise direction. The V-shaped loop 30 forms two prongs 31, 32, extending longitudinally outwardly from the outer clamping member 33. The inner clamping member 34 has a V-shaped loop 35 similar to the loop 21 in the clip 15. It will be noted that the two prongs or fingers 31, 32, serve as guides for the V-shaped end 35 and cause the clip 29 to move in a straight line as directed by the force exerted by the user against the straight end or handle 36.

The straight end 36 serves as a handle by means of which the clip may be easily manipulated into and out of engagement with papers with which the clip may be used. The V-shaped inner loop 40 35 provides a wedge action and a centering guide and causes easy slippage over the papers to be clipped. The free ends 11³ and 12³ terminate in a plane lying substantially in abutment with the straight end 36, and cannot dig in and scratch 45 the paper as is usually the case when removing paper clips of the "Gem" type having short legs which do not extend to the extreme end of the clip.

A paper clip of the character described will 50 fasten several sheets of paper firmly together, and when in operative position on a number of sheets, will prevent other sheets from slipping between the sheets clamped thereby.

As shown in Figure 7, there has been provided 55 a modified paper clip 37 similar to the clip 29 shown in Figure 6, but having an outer loop 38 bent into V-shape and lying outwardly in lengthwise direction. The inner clamping member 39 has a V-shaped loop 40 similar to the loop 35 60 in the clip 29. The V-shaped loop 40 forms two

prongs or fingers 41, 42 extending longitudinally outwardly from the inner clamping member 39. It will be noted that the two prongs or fingers 41, 42 serve as guides for the V-shaped end 38 and cause the clip 37 to move in a straight line as directed by the force exerted by the user against the straight end or handle 43. The free ends 11⁴, 12⁴ terminate in a plane lying substantially in abutment with the straight end 43 and cannot dig in and scratch the papers to which they may be applied. The handle 43 connects the inner clamping member 39 to the outer clamping member 44.

As shown in Figure 8, the modified clip 15' is formed from a continuous wire bent to form an outer clamping member 19 and an inner clamping member 20 both of U formation, the cross-bar of the outer clamping member being deflected longitudinally inwardly at 16 to form a loop portion having two fingers 17' and 18'. The inner clamping member 20 has a V-shaped formation 21 at the end adjacent the loop portion, the apex of the V-shaped formation 21 extending longitudinally outwardly in a direction opposite to the inwardly deflected loop portion on the outer clamping member, said clamping members being connected by a handle or straight cross-bar 22 at the end of the clip opposite the deflected end cross-bar, the ends of the wire 11', 12', terminating at points which are in substantial alignment with the cross-bar 22, the fingers 17', 18', of the outer clamping member being slightly bent in a direction laterally of the clip 15'.

While I have described and illustrated a number of embodiments of my invention, it will be understood that various changes and modifications can be made therein without departing from the spirit of the invention as defined by the appended claim.

Having thus described my invention, I claim:

A paper clip consisting of a continuous spring wire bent to form outer and inner clamping members of U formation, the cross-bar of the outer clamping member being deflected longitudinally inwardly to form a loop portion having two fingers, the inner clamping member having a V-shaped formation at the end adjacent the loop portion, the apex of the V-shaped formation extending longitudinally outwardly in a direction opposite to the inwardly deflected loop portion on the outer clamping member, the said clamping members being connected by a straight cross-bar at the end of the clip opposite the deflected end cross-bar, the two ends of the wire terminating at points which are in substantial alignment with the straight cross-bar, the said fingers of said outer clamping member being slightly bent in a direction laterally of said clip.

HENRY G. LANKEAU.
